UNITED STATES PATENT OFFICE

2,506,694

VALVE MEANS FOR LIQUID FUEL PUMPS

Ernest Ansley Watson and Richard Joseph Ifield,
Birmingham, England, assignors to Joseph Lucas Limited, Birmingham, England

Application April 6, 1945, Serial No. 586,966
In Great Britain February 23, 1944

Section 1, Public Law 690, August 8, 1946
Patent expires February 23, 1964

3 Claims. (Cl. 137—153)

1

This invention relates to valve means for liquid fuel pumps of the type having combined therewith means for automatically controlling the output in response to differing conditions.

In the accompanying sheet of explanatory drawings—

Figure 1 is a sectional side view of means constructed in accordance with the invention, and Figure 2 is a sectional view of a modified detail.

One form of pump to which the invention is applicable comprises a rotary cylinder block provided with a plurality of spring loaded plungers, the latter co-operating with a swash plate which is angularly adjustable for varying the pump output. The automatic adjustment of the swash plate is effected by a spring loaded piston contained in a cylinder embodied in the pump housing and connected by a rod to the swash plate. The two ends of the cylinder are interconnected by a restricted passage and liquid is supplied to one end of the cylinder from the delivery side of the pump. In association with the end of the cylinder remote from the end to which the pressure fluid is supplied is arranged a vent.

An example of a pump as above described forms the subject matter of Patent No. 2,403,371 (Serial No. 467,408).

In carrying the invention into effect as shown in Figure 1, in which the above mentioned vent is indicated by 21², a valve 20² for controlling the vent 21² is carried by one end of a lever 22², the latter being secured at a position intermediate its ends to a diaphragm 41² which serves as a fulcrum for the lever, and forms a dividing partition between two chambers 42², 43². In the chamber 42² is arranged a flexible capsule 26² which is supported at its opposite ends respectively by the end of the lever 22² remote from the valve 20² and by an adjustable abutment 14². The chamber 42² communicates in any convenient manner with the outer atmosphere, and the capsule 26² is responsive to atmospheric pressure. The valve 20² is situated in the other chamber 43², and is loaded by a spring 2² acting on the adjacent end of the valve lever 22². The chamber 43² also contains one end of a plunger 33² which is responsive to the fluid pressure at the delivery side of the pump, and which is arranged to act on the valve lever 22² at a position between the valve 20² and the diaphragm 41². The plunger 33² is slidably supported by a flanged cylindrical guide 44² extending through one side of the chamber 43², the guide being angularly adjustable, and the plunger being situated eccentrically in relation to the guide, so that the posi-

2

tion at which the plunger acts on the lever 22² can be varied by angular adjustment of the guide. At the end remote from the valve lever 22² the plunger 33² is supported by an abutment 45² on one side of another diaphragm 46² through which the fluid pressure at the delivery side of the pump can act on the plunger, this latter diaphragm being secured between the outer end of the guide 44² and a pipe connection 47² adapted to communicate with the said side of the pump.

Instead of the diaphragm 46² we may employ a cup-washer 46³ as shown in Figure 7, this washer being slidable in the adjacent end of the pipe connection 47², and being attached to the abutment 45² which serves to support the adjacent end of the plunger 33².

By this invention we are able to effect the control of the pump output by the actions of atmospheric and pump-delivery pressure in a very convenient manner. But the invention is not limited to the examples above described as subordinate constructional details may be modified to suit different requirements. Also the invention may be applied in substantially the same manner to the fluid operated governing mechanisms of pumps other than the example specified. Further we desire it to be understood that by atmospheric pressure we mean the pressure of any conveniently available air which may be the outer atmosphere, or the atmosphere in any room or compartment associated with the system to which the invention is applied, but not including compressed air supplied by a blower or the like to any part of the system.

Having thus described our invention, what we claim as new and desire to secure by Letters Patent is:

1. Pressure-fluid valving means comprising in combination a liquid vent, a valve controlling the vent, a lever carrying the valve, a pair of chambers containing opposite end portions of the lever, a diaphragm separating the chambers and attached to an intermediate part of the lever, a plunger responsive to liquid pressure and adapted to act on the lever, and a flexible capsule responsive to atmospheric pressure and adapted to act on the lever.

2. Pressure-fluid valving means comprising in combination a liquid vent, a valve controlling the vent, a lever carrying the valve, a pair of chambers containing opposite end portions of the lever, a diaphragm separating the chambers and attached to an intermediate part of the lever, a spring arranged in one of the chambers and acting on the lever, a plunger responsive to liquid

pressure and adapted to act on the lever, and a flexible capsule responsive to atmospheric pressure and adapted to act on the lever.

3. Pressure-fluid valving means comprising in combination a liquid vent, a valve controlling the vent, a lever carrying the valve, a pair of chambers containing opposite end portions of the lever, a diaphragm separating the chambers and attached to an intermediate part of the lever, a spring arranged in one of the chambers and acting on the lever, a plunger responsive to liquid pressure and adapted to act on the lever, and a flexible capsule responsive to atmospheric pressure and adapted to act on the lever, the valve being carried by the portion of the lever in the chamber containing the spring, the plunger being arranged to act on the lever at a position between the valve and diaphragm, and the capsule being arranged in the other chamber.

ERNEST ANSLEY WATSON.
